UNITED STATES PATENT OFFICE.

EMIL VOLK, OF NEW YORK, N. Y.

DESIGN FOR A BADGE OR EMBLEM.

SPECIFICATION forming part of Design No. 19,671, dated February 25, 1890.

Application filed December 17, 1889. Serial No. 334,115. Term of patent 7 years.

To all whom it may concern:

Be it known that I, EMIL VOLK, a citizen of the United States, residing at the city of New York, in the county of New York and State of New York, have invented and produced a new and original Design for Badges or Emblems, of which the following is a specification, reference being had to the accompanying drawing, forming a part thereof.

10 The said drawing represents the design in full, showing a stag's head, with wreath on both sides, over which flies an American eagle having in his beak a ribbon. Below the stag's head is a hunter's horn, under which are two 15 flags, with an American shield in center of plate at bottom of shield and also at top of eagle, and all of which is more particularly shown on the drawing accompanying, as follows:

A A represent two opposite curved portions of a wreath, joined at the top by a ribbon B, surmounted by an eagle C, above which is a segment or plate D. The lower ends of the wreaths join the American flags E E, with shield in center F below shield, a segment or 25 plate g connecting ends of flags E E. The said shield F is surmounted by hunter's horn d and stag's head G, which occupies center of the main shield.

What I claim is—

30 The design for a badge or emblem herein shown and described, the same comprising the entire combination, as shown in the accompanying drawing.

EMIL VOLK.
